UNITED STATES PATENT OFFICE.

FRANK P. HARTLEY, OF BANGOR, MAINE.

AUTOMATIC FIRE ALARM.

Application filed September 6, 1923. Serial No. 661,244.

To all whom it may concern:

Be it known that I, FRANK P. HARTLEY, a citizen of the United States, residing at Bangor, in the county of Penobscot and State of Maine, have invented certain new and useful Improvements in Automatic Fire Alarms; and I do declare the following to be a full, clear, and exact description of the invention, such as will enable others skilled in the art to which it appertains to make and use the same.

This invention relates to an improved automatic fire alarm of the type in which a spring-controlled portable signal may be caused to sound when a fire occurs and the temperature in a room rises above a predetermined point.

One object of the invention is to provide a signal of the character described in which the signal-sounding means and control means therefor may be permanently mounted upon a carrier plate detachably held in engagement with a hollow support in which the thermostat will be mounted so that when desired the carrier plate may be easily and quickly removed for cleaning or repairing, without it being necessary to disturb the thermostat.

Another object of the invention is to so construct this device that the thermostat may be positioned within a hollow support and the signal-carrying plate detachably secured upon the outer face of the support with the signal means extending externally and a control means carried by the plate extending into the support in position for engagement by the thermostat.

Another object of the invention is to provide an improved type of control in the form of a lever pivotally mounted beneath the signal-carrying plate and having a stem extending through the plate for engaging a latch forming part of the signal-sounding means, an abutment being provided intermediate the length of this lever so that it can be adjusted towards and away from the thermostat and thus cause the lever to be moved to release the latch only when the temperature in the room has reached a predetermined point.

This invention is illustrated in the accompanying drawings, wherein:

Figure 1 is a top plan view showing the improved device with the signal bell removed.

Figure 2 is a bottom plan view of the device.

Figure 3 is a vertical sectional view through the device with the bell in place.

Figure 4 is a view taken at right angles to Fig. 3 and showing the device partially in vertical section and partially in elevation.

This improved signal is provided with a support 1 which is in the form of a dome 65 and will preferably be formed of metal. It will thus be seen that the support is in the form of a hollow housing which is open at its lower end. A cross-bar or bridge 2 extends across the lower end portion of this dome 1 and has its end portions bent to provide upturned arms 3 having threaded openings formed therein so that fastener screws 4 may be passed through the walls of the dome and screwed into these openings to securely hold the bridge in place. A wire screen 5 is provided as a protector for the open lower end of the dome and has its peripheral portion turned upwardly to engage the inner face of the walls of the dome. This upturned portion of the screening 5 extends between the arms 3 and the walls of the dome so that when the screws 4 are put in place, the wire will be firmly gripped. The thermostat 6 is of a conventional construction and is positioned within the dome or support 1 and is provided with the usual neck portion 7 which extends from its upper face for engaging the signal control when the thermostat expands. A 90

threaded stem 8 extends downwardly from this thermostat and passes through an opening formed in the bridge and also through the wire screening. A securing nut 9 will then be put in place and will serve not only as means to secure the thermostat in place but will also serve as means for assisting in holding the screen 5 in place. The upper portion or head of this dome has been provided with an opening 10 which is elongated 100

and shaped as shown in Fig. 2 and extends substantially diametrically of the dome. Adjacent one end and at one side of the opening 10, there has been provided a slot 11 which extends transversely of the opening and adjacent the other end of the opening and at the opposite side thereof from the slot 11, a tongue 12 has been cut from the dome and bent upwardly as shown in Fig. 3 to provide a latching tongue, to releasably hold the signal carrier in place.

This signal carrier is in the form of a plate 13 formed of a suitable metal which will preferably be circular in shape to conform to the shape of the dome but of course may be of any desired shape. This plate rests upon the top of the dome and covers the opening 10. At one point above the circumference of this plate, there has been provided a tongue 14 which is bent as shown in Fig. 3 so that it will be offset with respect to the rest of the plate and positioned beneath the plane thereof. This tongue 14 is of a proper width to permit of it being passed through the slot 11. It will thus be seen that the tongue may be passed into the slot 14 with the plate in a tilted position and the plate then swung downwardly into flat engagement with the upper wall or head of the dome. When in this position, the tongue 14 will engage the inner face of this head of the dome and the latching tongue 12 will pass through an opening 15 formed in the plate. This latch will then engage the plate as shown in Fig. 3 and the plate will be securely held in engagement with the dome but may be easily and quickly removed by inserting a screw-driver or other similar prying device between the dome and the lip portion 16 of the plate.

The signal means is carried by the plate 13 and is provided with a signal bell 17 which is held upon the shaft 18 by means of a fastener 19 which is threaded upon the shaft 18 and provided with a ring 20 so that by grasping the ring 20 and turning it, the shaft may be rotated in one direction. This shaft 18 forms the main shaft 50 of the clockwork indicated in general by the numeral 21 and when the shaft is rotated by means of the fastener 19 and ring 20, the spring 22 will be wound. This clockwork is of the usual construction in connection with the alarm mechanism of a clock and includes the usual striker shaft 23 having a side pin 24 engaged by the tongue 25 of the latch strip 26. This latch strip 26 is formed of resilient material and is secured upon the upper face of the carrier plate 13 and has its free end positioned above a stem 27 which passes slidably through the plate and has its upper end enlarged to provide a head 28 to limit its downward movement. This stem 27 is

threaded and has its lower end portion passing through an opening formed in the free end of a lever 29 positioned beneath the plate and pivotally mounted between the ears 30 formed by tongue cut from the plate 13 and bent downwardly. It will thus be seen that when the plate 13 is in position, the control means which includes the lever 29 and stem 27 will be positioned within the dome 1. In order to secure the stem 27 to the free end of the lever, there have been provided securing nuts 31 which are threaded upon this stem and engage the upper and lower faces of the lever. These nuts will firmly hold the stem in engagement with the lever, but will permit adjustments. A side tongue 32 extends from the lever intermediate its length and carries an abutment screw 33 which has its threaded shank passed upwardly through a threaded opening formed in this tongue 32 and its head positioned above the abutment lug 7 extending upwardly from the thermostat 6. A lock-nut 34 is provided upon this abutment screw to engage the side tongue 32 and securely lock the abutment in an adjusted position. It will thus be seen that the abutment nut can be secured a desired distance above the lug 7 and the lug 7 thus caused to only engage the abutment when the thermostat has been expanded the amount which will take place when the temperature has risen to a predetermined degree of heat.

When this device is in use, it will be mounted at a proper point in a room by any suitable mounting means, and with the abutment screw set at the proper position and secured by the lock nut 34, the tongue 14 will be passed through the slot 11 and the carrier tilted downwardly into the position shown in Fig. 3. The spring can then be wound and the device is ready for use. When the temperature rises above a predetermined degree of heat, the expanding thermostat 6 will engage the abutment and swing the lever 29 upwardly, thus raising the stem 27 so that its head 28 will engage the free end portion of the spring latch 26 and move this latch upwardly to a position in which the tongue thereof will be out of engagement with the side pin of the striker shaft. The clockwork will then be released and the striker will be operated in the usual manner to sound the bell 17. It will of course be understood that the device could be modified so that contraction of the thermostat by a decrease in temperature could cause sounding of the alarm. If it is necessary to clean the clockwork mechanism or make any repairs to the same or adjust the abutment 33 to change the temperature at which the signal will be sounded, it is simply necessary to insert a screw-driver or any other prying device beneath the lip 16 and tilt the plate 13 upwardly. This will

release the plate from the latch 12 and the plate can be swung upwardly and entirely removed from the dome 1. The signal means and signal control means will be bodily removed with this plate and the proper repairs or adjustments can be made and the carrier plate and signal means replaced, without it being necessary to reset the thermostat within the dome.

10 A fire alarm has thus been provided which is very effective in operation and which can be easily and quickly repaired or adjusted without the thermostat which is very delicate being disturbed.

15 I claim:

1. In a device of the character described, a support having a socket and a latching tongue spaced from the socket, a signal carrier resting upon said support and having a tongue moved into and out of said socket by tilting of the carrier, the carrier being tilted into and out of engagement with said latching tongue, a signal carried by said carrier, a signal control carried by said carrier, and a thermostat carried by said support for engaging said control and causing movement thereof to permit operation of the signal.

2. In a device of the character described, a support, resilient locking means carried by said support, a signal carrier resting upon said support and snapped into and out of engagement with said resilient locking means for quick detachment from said support, signal means and signal control means carried by said carrier and bodily removable therewith, and thermostatic means carried by said support and positioned for engag-

ing said control means and causing movement thereof to permit operation of the signal when the thermostat is affected by a predetermined change in temperature.

3. In a device of the character described, a support, a signal carrier removably connected with said support, spring-operated signal means carried by the outer face of said carrier and including a latch normally in an operative position, a lever pivotally connected with said carrier and positioned beneath the same, a stem extending from the lever through said carrier for engaging said latch and moving the latch to a releasing position when the lever is moved upwardly, a thermostat mounted in said support, and an abutment carried by said lever and positioned above said thermostat for engagement thereby to permit movement of the lever to release the latch, said abutment being adjustably mounted for movement towards and away from the thermostat.

4. A device of the class described comprising a hollow supporting base having a relatively large opening in its top, a thermostat mounted within said base below said opening, a carrier plate closing said opening, a signal mounted on said plate, operating means for said signal mounted on said plate, and control means carried by said plate and arranged for co-action with said thermostat, said plate and all of the parts carried thereby being removable from said opening as a unit.

In testimony whereof I have hereunto affixed my signature.

FRANK P. HARTLEY.
